(57) **CLAIM**

I claim the ornamental design for a coupon card, as shown and described.

DESCRIPTION

FIG. 1 is a perspective view of a coupon card, showing my new design;

FIG. 2 is a front elevational view thereof;

FIG. 3 is a rear elevational view thereof;

FIG. 4 is a left-side elevational view thereof, the right-side elevational view being a mirror image thereof; and,

FIG. 5 is a top plan view thereof, the bottom plan view being a mirror image thereof.

The broken lines in FIGS. 1 and 2 depict environmental matter that forms no part of the claimed design.

1 Claim, 3 Drawing Sheets

FIG. 1

FIG. 2

FIG. 3

FIG. 4

FIG. 5
